ELECTRICAL SWITCH

Francis C. Schmidt, Logansport, Ind.

Application February 26, 1957, Serial No. 44,989

Term of patent 14 years

(Cl. D26—13)

FIG. 1

FIG. 2

FIG. 3

FIG. 4

FIG. 5

FIG. 6

Figure 1 is a front elevational view of an electric switch, showing my new design.

Figure 2 is an elevational view looking at the right hand side of the switch as viewed in Figure 1.

Figure 3 is a top view.

Figure 4 is a rear elevational view.

Figure 5 is a perspective view looking downwardly at the front and right hand sides of the switch.

Figure 6 is a similar view looking at the rear and right hand sides of the switch.

I claim:

The ornamental design for an electric switch, as shown.
